Attorney

UNITED STATES PATENT OFFICE.

JOHN H. GILBERT, OF PLANT CITY, FLORIDA.

LOCK.

1,240,839.

Specification of Letters Patent. Patented Sept. 25, 1917.

Application filed July 2, 1917. Serial No. 178,222.

To all whom it may concern:

Be it known that I, JOHN H. GILBERT, a citizen of the United States, and resident of Plant City, in the county of Hillsborough 5 and State of Florida, have invented certain new and useful Improvements in Locks, of which the following is a specification.

This invention relates to new and useful improvements in locks, and more particularly to a new and improved type of hasp fastener, which is especially adapted for application on barn doors, warehouse doors or the like, and the primary object of the invention is to provide a device of this character which is quickly adjusted to operative or inoperative position, without the employment of a key.

Another object of the invention is to provide a device of this character which is easily and simply constructed, inexpensive to manufacture, and one which will be very efficient in operation.

With these and numerous other objects in view, my invention consists of the novel 25 features of construction, combination and arrangement of parts which will be herein referred to and more particularly pointed out in the specification and claims.

In the accompanying drawings:—

30 Figure 1 is a perspective view of the lock; Fig. 2 is a vertical section through the same; and

Fig. 3 is a horizontal section.

In describing my invention I shall refer 35 to the drawings in which similar reference characters designate corresponding parts throughout the several views.

The numeral 1 designates a base plate on which is positioned a cylindrical casing 2 40 having formed in its top 3 an aperture 4. This casing 2 forms a keeper for the lock. Pivotally mounted on the inner surface of the top 3 and having a handle 5 projecting through the wall of said cylinder, is a pivoted latch 6 for a purpose to be hereinafter more fully described.

The base 1 is provided with a projecting portion 7 having an aperture therethrough, and disposed in alinement with said aperture 50 and mounted on the projection 7 is a tubular casing 8 which is externally threaded as shown at 9. A supplemental internally threaded casing 10 is adapted to be cooperatively related with the said first mentioned casing, and the top of the casing 10

has an aperture therethrough adapted for alinement with the aperture through the projection 7, and consequent alining with the bore of the casing 8.

The hasp lock 11 of this device is of the usual type being provided with a main portion 12 that is positioned through the alining apertures in the casing, and projection 7 and is formed with a hook bent portion 13. The main portion 12 of the hasp extends 60 parallel with the keeper 2 through the casings, and above and below the same. The lower projecting end of said main portion has a crank 14 formed therein, so that the hasp may be rotated in a manner to be 65 hereinafter more fully described. The portion of the hasp that is positioned through the casings is slightly reduced, and a collar 15 is mounted on said portion of the hasp, said collar being formed with outwardly 70 projecting flanges that are adapted to engage the edges of the aperture in the top of the casing 10. This connecting collar reciprocably, but non-rotatably connects the hasp with the outer movable casing 10. The 75 bent hook portion 13 of the hasp 11 is formed with a notch 16 therein for a purpose to be hereinafter more fully described.

In operation when the various parts of the device are positioned as shown in Fig. 1 80 of the drawings, when it is desired to operate this type of lock, the crank 14 is operated and this will swing the hasp 11 around until the bent portion 13 is disposed above the keeper 2, and directly in alinement with the aperture 4 in the top thereof. When the parts are in this position, the outer casing 10 is rotated, the outer surface of said casing being roughened so as to facilitate this operation, and consequently the 85 said casing will be moved down upon the inner casing 8, owing to the co-operative threaded engagement between these casings. As the main portion of the hasp 12 is reciprocably but non-rotatably connected with the outer movable casing 10, consequently 90 upon downward movement of said casing the hasp will be correspondingly moved, and the projecting bent end 13 will be moved down through the aperture 4 into the keeper 2. When the casing 10 has reached the limit of its downward movement, the end 13 of the hasp will be positioned within the keeper, and upon moving the pivoted latch 6 across said keeper, the latch will 95 100 105 110

gage the notch 16 in the end of the hasp, and prevent accidental withdrawal thereof, should the outer casing 10 work up. To release the device from operative locked position, it is obvious that the outer casing 10 is merely rotated in the opposite direction, whereupon the hasp will be adjusted longitudinally, and moved from out of engagement with the keeper. Upon operation of the crank 14 the hasp will be rotated and the bent portion will be swung out of operative relation with the keeper. This type of lock will form a very efficient, and quickly operated device especially adapted for use on barn doors, warehouse doors or the like. The longitudinally adjustable handle may be quickly swung out of operable relation when it is not desired to use the device, and the various parts of said device are disposed in locked position, the pivoted latch member 6 forms a supplemental locking means to absolutely prevent accidental displacement. The operation of this type of lock is very simple, and is absolutely keyless.

From the above description taken in connection with the accompanying drawings, it is thought that a clear and comprehensive understanding of the construction, operation and advantages of my invention may be had, and while I have shown and described the device as embodying a specific structure I desire that it be understood that such changes may be made in said structure as do not depart from the spirit and scope of the invention as claimed.

Having fully described my invention,

what I claim as new, and desire to secure by Letters Patent, is:—

1. A device of the class described including a keeper, a longitudinally adjustable rotatable hasp disposed substantially parallel therewith and having one end adapted for engagement with said keeper, and a crank on the lower end of said hasp whereby the same is adapted to be rotated out of operation with the keeper. 40 45

2. A device of the class described including a keeper, a hasp disposed substantially parallel therewith, an externally threaded tubular casing carried by the keeper through which the hasp is adapted to be slidably positioned, and internally threaded casing cooperatively related with the first mentioned casing, and means for reciprocably but non-rotatably connecting the last mentioned casing with the hasp. 50 55

3. A device of the class described including a keeper, a rotatable and longitudinally adjustable hasp of a greater length than said keeper disposed substantially parallel therewith, means for moving said hasp longitudinally whereby one end is adapted for engagement with the keeper, means in said keeper for locking said end of the hasp when positioned therein, and a crank on the other end of the hasp for rotating the same when the first mentioned end is disengaged from the keeper. 60 65

In testimony whereof, I affix my signature hereto.

JOHN H. GILBERT.
